GUSTAV B. PETSCHÉ, OF PHILADELPHIA, PENNSYLVANIA, ASSIGNOR TO SOUTHWARK FOUNDRY & MACHINE COMPANY, OF PHILADELPHIA, PENNSYLVANIA, A CORPORATION OF PENNSYLVANIA.

WATER-COOLED PISTON FOR GAS-ENGINES.

967,551.

Specification of Letters Patent. Patented Aug. 16, 1910.

Application filed January 10, 1905. Serial No. 240,521.

To all whom it may concern:

Be it known that I, GUSTAV B. PETSCHÉ, a subject of the Emperor of Germany, residing in the city and county of Philadelphia, 5 in the State of Pennsylvania, have invented a certain new and useful Improvement in Water-Cooled Pistons for Gas-Engines, of which the following is a true and exact description, reference being had to the accompanying drawings, which form a part thereof.

My invention relates to gas engines and particularly to the piston construction used in connection with gas engines, my object 15 being to provide a piston made up of a piston center and a bull ring, both parts of which can be and are kept cool by circulating water through them.

The nature and preferred construction of 20 my piston will be best understood as described in connection with the drawings in which it is illustrated and in which—

Figure 1, is a side elevation of a gas engine coupled to a blowing engine and utilizing 25 my improved piston, the said figure indicating how water can be supplied to and withdrawn from the piston. Fig. 2, is a central vertical section through one of the gas engine cylinders and through the distance 30 piece separating the two cylinders shown in Fig. 1, the piston and circulating ports being partly shown in section. Fig. 3, is an enlarged view of the piston, taken on the same section as shown in Fig. 2 with the piston rod shown in full lines. Fig. 4, 35 is a cross-section on the line 4—4 of Fig. 3 and Fig. 5, is a cross-section on the line 5—5 of Fig. 3.

A, indicates the bed plate of the engine, 40 B, the engine frame, C, the blowing engine connected therewith, D, and D' the gas engine cylinders set tandem, E, the distance piece between the cylinders having, as shown, a removable top, part E², and removable end piece E', which construction forms the subject matter of my other application for Letters Patent filed 30th December, 1904, Serial Number 238,919.

F, is a sliding crosshead to which the end 50 of the piston rod H, is secured; F', a sliding crosshead moving in the distance piece

E, and to which the ends of the piston rods H, and H', are secured, the other end of the piston rod being supported on the sliding crosshead F².

G, and G', indicate pistons of the two cylinders, and H, and H', the piston rods connected with the two pistons and connected together through the sliding crosshead, as indicated in Fig. 2.

I, is the piston center and J, the bull ring of the piston.

The piston rods, see Fig. 2, are formed with central longitudinal water passages K and K², which open through the side of the 65 piston rod at the point where the piston is secured to it through ports K', and K³, the passages K, and K², being entirely separate from each other.

At L, I have shown a jointed water conduit connected to the passage K, of the rod H, through a lateral port K⁴, while the outer end of the rod H', is connected to a jointed water conduit O. The water passages in the piston rods are closed at the ends which are 75 secured to the crosshead F', as by plugs K⁶, K⁷, see Fig. 2, and the passages of the two abutted rods are connected together through a pipe N, coupled by lateral ports K⁵, K⁸, as shown.

The piston center I is formed with the annular inlet passage or chamber I¹ which (Fig. 3) is in communication with ports K¹ of the rod H. A series of ports I² lead from the chamber I¹ at one side of the piston rod 85 (see Fig. 4) into axial chambers or passages I³ formed in the piston center. The chambers I³ communicate adjacent the right hand end of the piston center, as seen in the drawings, with an annular passage or chamber I⁴. On the opposite side of the piston rod the 90 piston center has formed in it a series of axial passages or chambers I⁵ which communicate at one end with the passage I⁴ and at the other end with a semi-annular passage I⁶. A series of ports I⁷ lead from the semi-annular passage I⁶ to the left hand end of the piston center. The piston center is also provided with an annular outlet chamber I¹⁰ 95 in communication with the outlet ports K³. Ports I⁸ connect the annular passage I¹⁰ with a semi-annular passage I⁹ located on

the opposite side of the piston rod from the passage I^6 . Ports I^{11} lead from the passage I^8 to the adjacent end of the piston center.

The outer piston portion or bull ring J , 5 comprises a cylindrical portion J^1 having an inwardly extending flange J^2 at one end. The cylindrical portion of the bull ring surrounds the piston center with the flange bearing against the end of the piston center 10 as shown in Figs. 2 and 3. The bull ring is formed at one side of the piston rod with a set of axial passages J^5 which are connected adjacent one end of the bull ring by a semi-annular passage J^4 from which lead ports J^3 15 communicating with the ports I^7 of the piston center. At the opposite end of the bull ring the passages J^6 are connected by an annular passage or chamber J^6 . On the opposite side of the piston rod from the passages J^6 , 20 the bull ring has formed in it a set of axial passages J^7 which communicate with the passage or chamber J^6 . The passages J^7 are also connected by a semi-annular passage J^8 diametrically opposed to the passage J^4 . 25 Ports J^9 leading from the passage J^8 register with the ports I^{11} .

It will be seen that the water entering, for instance through the conduit L and the rod passage K , will pass through the ports K^1 to the annular chamber I^1 of the piston center. 30 From there the water passes through the ports I^2 to the passages I^3 and from there through the annular passage I^4 to the passages I^5 and thence through the ports I^7 35 into the bull ring through the ports J^8 . In the bull ring the water passes from the semi-annular passage J^4 through the passages J^5 to the annular chamber J^6 and thence through the passages J^7 to the semi-annular 40 passage J^8 whence it passes through the ports J^9 into the ports I^{11} of the piston center. From the ports I^{11} the water passes through the passage I^8 and ports I^9 to the outlet chamber I^{10} of the piston center and 45 thence through the ports K^3 into the piston rod passage K^2 . From the piston rod passage K^2 the water passes through the pipe N to the ports K^6 of the piston rod N^1 and thence through the similar piston of the 50 other cylinder.

It will be observed that the circulating passages in the piston center and bull ring sections of the piston are connected in series with each other and with the inlet ports K' 55 and K^3 so that the water passing into the piston through ports K' passes successively through ports and passages in the piston center and ports and passages in the bull ring on its way to the outlet ports K^3 . In 60 the particular construction illustrated, the water passes to the outlet ports K^3 from the ports and passages in the bull ring through another set of ports and passages in the piston center.

65 While the special arrangement of ports in

the piston center and bull ring are well adapted for an efficient circulation of water therethrough, it will be understood that I do not limit my invention to this particular system which is capable of extended variation. 70

Having now described my invention what I claim as new and desire to secure by Letters Patent is,

1. In combination with a hollow piston rod having inlet and outlet passages, a piston center provided with inlet and outlet chambers adapted to communicate with the passages in said rod, and having a circulating system of passages formed in it and communicating with said inlet and outlet chambers and a bull ring having an annular portion encircling said center and provided with circulating passages which have portions extending axially in said annular portion and which, when the ring is fitted to the center, connect with and form continuations of the circulating passages of the center. 80

2. In a gas engine, the combination with a piston rod having water circulating passages therein, of a piston made up in sections, one of which has an annular portion encircling the other section each of said sections having water circulating passages therein, the passages in one section being 90 connected in series with those in the other and also with the passages of the piston rod, to constitute a water circulating system, the passages in the section having said annular portion having portions extending axially 95 in said annular portion. 100

3. A gas engine piston made of an inner part I and an outer part J , the inner part I being adapted to be secured to a hollow piston rod and being formed on one side 105 with a set of axial chambers I^3 and on the other side with a set of axial chambers I^6 , said inner part also having formed in it an annular chamber I^4 connecting the chambers I^3 and I^6 , an inlet chamber I^1 connected to 110 the chambers I^3 by ports I^2 and an outlet chamber I^{10} and passages I^9 , I^8 and I^{11} communicating therewith, and the outer part J being formed at one side with a set of axial chambers J^6 communicating with the chambers I^6 and at the other side with a set of 115 axial chambers J^7 which communicate with the passages I^{11} , said outer part J also having the passage J^8 connecting the passages J^6 and J^7 . 120

4. A gas engine piston comprising a center portion and an outer portion, said center portion being formed with an inlet chamber and at one side with a series of axial passages communicating with the inlet chamber, and at the other side with another set of axial passages communicating adjacent one end of the center portion with a set of ports, said center portion also having a passage adjacent the opposite end of the 125 130

center portion, connecting said two sets of passages, and an outlet chamber and passages communicating therewith, said outer piston portion being provided at one side 5 with axially extending passages communicating with said ports of the center portion and at the opposite side with another set of axial passages communicating with the passages communicating with the outlet cham-

ber of the center portion, said outer piston 10 portion being also provided with a passage connecting said two sets of axial passages formed in it.
